UNITED STATES PATENT OFFICE.

CHARLES B. DALZELL, OF LITTLE FALLS, NEW YORK, ASSIGNOR TO D. H. BURRELL & COMPANY, OF LITTLE FALLS, NEW YORK.

PNEUMATIC CLEANING-TOOL.

936,222.

Specification of Letters Patent.

Patented Oct. 5, 1909.

Application filed May 22, 1909. Serial No. 497,588.

To all whom it may concern:

Be it known that I, CHARLES B. DALZELL, a citizen of the United States, residing at Little Falls, in the county of Herkimer and 5 State of New York, have invented a new and useful Improvement in Pneumatic Cleaning-Tools, of which the following is a specification.

This invention relates to currycombs and 10 other cleaning tools or implements in which an air current is employed for removing the hair, dirt or loosened foreign matter from the comb, tool or implement.

The object of this invention is to provide 15 a simple and efficient tool of this character in which the hair, dirt or loose foreign matter will be thoroughly and quickly removed by the air current, and in which the walls of the tool are so arranged as to form one or 20 several passage ways through which a constant and strong current of air passes when the tool is in use, thus serving to remove the foreign matter from all parts of the tool, preventing the clogging of the air passage 25 by accumulations of foreign matter therein, and thoroughly cleaning the hide or other surface to which the tool is applied.

In the accompanying drawings, consisting 30 of two sheets: Figure 1 is a front elevation of a currycomb and its connections embodying the invention. Fig. 2 is a longitudinal section of the same on line 2—2, Fig. 1. Fig. 3 is a transverse section thereof on line 3—3, Fig. 1. Fig. 4 is a fragmentary longitudinal section of the same, showing a modified form of connection between the comb and suction pipe. Figs. 5, 6 and 7 are front elevations of combs of modified construction. Fig. 8 is a longitudinal section of a 40 cleaning tool in which the walls on the face of the tool are made of rubber or other flexible material, the section being taken on line 8—8, Fig. 10. Fig. 9 is an end elevation of this tool. Fig. 10 is a face view of 45 the same.

Like reference characters refer to like parts in the several figures.

The currycombs shown in Figs. 1—7 each 50 comprise a flat back or base plate A of suitable shape having an opening or port a which opens into a suction chamber B connected by a suction pipe C C' with any suitable device (not shown).

Referring to Figs. 1, 2 and 3 the plate A 55 is provided on its front side with an out-

wardly or forwardly projecting comb wall D which forms between its convolutions an air passage way which is open at one end for the admission of the air and communicates at the other end through the opening a with the suction chamber B and pipe C C'. The comb wall D may be provided in its edge with serrations or dull teeth d, or may be otherwise so formed as to loosen the hair and dirt when the comb is applied to the hide of the animal. In this construction the back plate A is oblong in shape, having its suction opening a located at its middle. The comb wall D extends in an elongated spiral direction, or convolute shape around this opening and terminates at the outer edge of the plate A, thus forming on the face of the plate a spiral or convolute air passage E having an air inlet opening e at its outer end at the edge of the plate A and communicating at its inner end with the suction opening a. The suction chamber B is secured to the back of the plate A around the opening a and to the pipe C which is arranged in a plane parallel with the back plate, so that the pipe can be conveniently used as a handle for manipulating the comb. The two sections C and C' of the suction pipe are preferably connected by a ball and socket joint F, which permits freedom of movement of the comb in use. Any other suitable connection can, however, be used for connecting the suction pipe with the back of the comb.

In Figs. 1—3, the plate A, suction chamber B and pipe C are permanently secured together, while in Fig. 4, a modified construction is shown in which the suction chamber is permanently secured to the pipe C, and the comb is detachably secured to said chamber by a bolt h which passes through the rear wall of the suction chamber and engages a screw-threaded opening in a lug i on the back plate A. A packing K is placed between the edge of the suction chamber and the back plate A for forming an air tight joint between the parts. The comb can thus be readily attached to and detached from the suction pipe when desired and can be renewed when worn out.

In Figs. 5, 6 and 7 are shown combs of modified construction in which the walls and the suction opening are arranged in different positions. In Fig. 5 the comb walls L are arranged to form a zigzag air passage l on

105

110

the face of the comb, having its inlet opening *m* at one end and communicating at the other end with the suction device through the opening *a* which is located at the closed 5 end of the passage. In Fig. 6 the comb walls *N* are similarly arranged but the passage way *n* is open at both ends *o* and the suction opening *a* is located in the passage way intermediate of its ends, so that the air 10 is drawn into the passage way at both ends thereof. In Fig. 7 the comb is of star shape, the walls *P* forming a passage way about the outer portion of the plate *A*, which passage way has an opening *q* at one end for the ad- 15 mission of the air and communicates at its other end with a central pocket *r* formed by the inner wall of the passage way and having the suction opening *a* located centrally therein.

20 When the comb is placed upon the hide of the animal, the open or face side of the air passage way formed between the comb walls is practically closed by the hair and hide of the animal, and air can only enter the passage way through the opening in its end at the outer edge of the comb. The air current so entering this passage way is confined therein between the comb walls and follows these walls and passes out through 25 the suction opening at the inner end of the passage way. By admitting the air to the passage way through a relatively large and practically unobstructed opening at the end thereof and confining it between the comb walls, a strong and steady air current is produced which travels swiftly through the passage way and comes into contact in its course with all parts of the comb and removes all dirt and other foreign matter 30 which are loosened by the movement of the comb or the action of the air current in passing over the hide. Although considerable suction can in this manner be applied to the comb, it causes no discomfort to the animal by drawing the hide too firmly 35 against the comb, or otherwise, and it does not interfere with the free movement of the comb over the hide. The passage between the walls is of such size and the current of air of such strength that there is no danger 40 of the passage becoming clogged by accumulations of matter therein.

The cleaning tool represented in Figs. 8-10 is provided on its face side with a convolute cleaning wall *S* having a plain edge 45 or face and preferably formed of soft rubber. The outer end of this wall is tapered or otherwise shaped to form an air inlet *s* for the convolute air passage *t* which communicates at its inner end with the suction opening *a*. The cleaning wall *S* is preferably formed integrally with a back plate *T*

which contains a metallic stiffening plate *t'* embedded therein. The latter is provided with a threaded lug *u* for the reception of 65 a fastening bolt *h* by which the tool is removably attached to the suction chamber. A tool of this construction is very efficient and convenient for cleaning animals and may also be used for other purposes. 70

I claim as my invention:

1. A pneumatic cleaning tool provided on its face side with walls which form between them an air passage having at one end an air inlet and having at the opposite end an 75 opening adapted to communicate with a suction device, substantially as set forth.

2. A pneumatic cleaning tool comprising a plate having a suction opening therein, and walls arranged on the face of said plate 80 and forming thereon an air passage which is open at one end and communicates at its opposite end with said suction opening, substantially as set forth.

3. A pneumatic cleaning tool comprising 85 a plate having a suction opening therein, and walls arranged on the face of said plate and forming thereon an air passage which extends over said face and has at one end an air inlet arranged at the outer edge of 90 said plate, said passage communicating at its opposite end with said suction opening, substantially as set forth.

4. A pneumatic cleaning tool provided on its face side with a convolute wall forming 95 between its convolutions an air passage having at one end an air inlet and adapted to communicate at its opposite end with a suction device, substantially as set forth.

5. The combination of a pneumatic cleaning tool provided in its back with a suction opening and having on its face an air passage which is open at one end and communicates with said opening, of a suction chamber which is open at its front, and 105 means for detachably securing said tool to said suction chamber, substantially as set forth.

6. The combination of a pneumatic cleaning tool provided in its back with a suction opening and having on its face an air passage which is open at one end and communicates with said opening, of a suction chamber which is open at its front and bears 110 against the back of said comb, and a removable fastening device connecting said suction chamber with said tool, substantially as set forth.

Witness my hand in the presence of two subscribing witnesses.

CHARLES B. DALZELL.
